UNITED STATES PATENT OFFICE.

JAMES L. FOLSOM, OF SPRINGFIELD, MASSACHUSETTS, ASSIGNOR TO THE HARTFORD CARPET CORPORATION, OF THOMPSONVILLE, CONNECTICUT, A CORPORATION OF CONNECTICUT.

DESIGN FOR CARPET OR RUG.

43,920.

Specification for Design.

Patented Apr. 29, 1913.

Application filed March 6, 1913. Serial No. 752,496. Term of patent 3½ years.

To all whom it may concern:

Be it known that I, JAMES L. FOLSOM, a citizen of the United States, residing in Springfield, in the county of Hampden and State of Massachusetts, have invented a new, original, and ornamental Design for a Carpet or Rug, of which the following is a specification, reference being had to the accompanying drawing, forming part thereof.

The figure is a face view of approximately a quarter section of a carpet or rug showing my design.

I claim:

The ornamental design for a carpet or rug as shown.

JAMES L. FOLSOM.
